FRED H. SHARP, OF SALINA, KANSAS

APPARATUS FOR RESIZING PISTONS

Application filed July 15, 1926. Serial No. 122,714.

The present invention relates to means for increasing the size or diameter of pistons and like articles, and is particularly intended for enlarging or increasing the diameter of pistons that have become worn. The object is to provide means whereby such pistons can be brought to proper diameter with ease and expedition and at relatively small cost, thus materially increasing the life of such articles.

10 In the accompanying drawings:—

Figure 1 is a side elevation of the novel implement by means of which the process can be carried out,

15 Figure 2 is a longitudinal sectional view therethrough showing a piston in place,

Figure 3 is a horizontal sectional view on the line 3—3 of Figure 2,

Figure 4 is a view in elevation of a piston that can be treated,

20 Figure 5 is a detail perspective view of the piston expanding wedge.

In the embodiment disclosed, a metal sleeve 6 is employed, that is longitudinally slotted as shown at 7, and is thus expandable 25 and contractile. This sleeve is preferably provided on one side with a lug 8 carrying an outstanding handle 9. The sleeve is furthermore provided on opposite sides of the slit 7 with outstanding lugs 10 and 11.

30 Through one of these lugs extends a rotatable contracting stem 12 that is threaded, as shown at 13 in the other lug 11. The stem preferably has a winged head 14, by which it can be readily turned. Through the other 35 lug 11 is threaded an expanding screw 15 that bears against the lug 10 and is also provided with a winged head 16. It will thus be evident that by manipulating the screws 12 and 15, the sleeve can be expanded or contracted as desired.

40 Fulerumed on the stem 12 is a hand lever 17, bowed, as illustrated at 18, so that the screw 15 will not interfere with its movement. Adjacent to the fulcrum, the lever is 45 provided with a bill 19 that is in the form of an inwardly pointed wedge, which wedge is adapted to move through the slit 7 of the sleeve 6 into and out of the interior of said sleeve, as will be apparent by reference to 50 Figure 2. The article to be treated is shown

in the form of a well known type of piston 20 for an internal combustion engine. This piston is provided with a longitudinal slot 21. In the present embodiment the slot extends diagonally to the longitudinal axis of 55 the piston.

In using this device, and assuming that it is desired to increase the diameter of a worn piston, as 20, the internal diameter of the sleeve 6 is first set to a diameter greater than 60 that desired for the said piston 20. The piston 20 is then heated, which will expand it to a certain extent, but less than the internal diameter of the sleeve. After being heated, the piston is introduced into the sleeve with 65 the central portion of the slot 21 in line with the central portion of the slit 7 of the sleeve 6. The lever 17 is then moved to a position to carry the wedge 19 into the central portion of the slot 21, whereby the heated piston is expanded to the diameter of the sleeve, 70 as illustrated in Figures 2 and 3. The sleeve with the mechanically expanded piston is then plunged in water or oil and thereby cooled, which causes the piston to shrink substantially to the desired diameter. The piston is then removed from the sleeve and will 75 be at substantially the desired diameter.

75 As an example, it has been found practical to expand a worn piston .030 of an inch. Assuming that it is necessary to enlarge the piston to .005 of an inch oversize, the sleeve should then be set by the use of suitable micrometers at .035 of an inch. The piston is then heated until it has expanded to the 80 extent of .030 of an inch, which expansion, when heating, can be readily determined by the use of micrometers. When this heat expansion has been reached, the piston, while 85 thus heated, is inserted in the sleeve that has already been set at .035 of an inch. The wedge is then inserted in the slot in the piston, and the piston mechanically expanded thereby until it snugly fits in the sleeve. This enlarges the piston to the extent of .005 90 of an inch above the heat expansion. The cylinder with the piston thus inserted and mechanically expanded is then submerged in water or oil, and thereby cooled. This causes shrinkage of the piston to .005 of an 95 100

inch larger than in the beginning, as a contraction of .030 has taken place in the process of cooling. It has been found desirable that the wedge 19, when being inserted in the slot, moves both inward and longitudinally at the same time, this causing a more even expansion.

From the foregoing, it is thought that the construction, operation and many advantages 10 of the herein described invention will be apparent to those skilled in the art, without further description, and it will be understood that various changes in the size, shape, proportion and minor details of construction, 15 may be resorted to without departing from the spirit or sacrificing any of the advantages of the invention.

What I claim, is:

1. A piston sizing device comprising a 20 slotted piston-encircling sleeve, means connecting the portions on opposite sides of the slit for expanding and contracting the sleeve, and a piston expanding wedge that passes through the slit of the sleeve.
2. A piston sizing device comprising a 25 slotted piston-encircling sleeve, means connecting the portions on opposite sides of the slit for expanding and contracting the sleeve, and a piston expanding-wedge that passes 30 through the slit of the sleeve and is mounted on said expanding and contracting means.
3. A piston sizing device comprising a 35 slotted piston-encircling sleeve having outstanding lugs on opposite sides of its slit, an expanding screw on one lug bearing 40 against the other lug, a contracting screw threaded on one lug and bearing against the other lug, and a lever fulcrumed on one of the screws and having a wedge that passes through the slit.
4. In combination, a sleeve having walls 45 and of a diameter to encircle a heated engine piston and confine it to a predetermined diameter while maintaining its external contour unchanged, said walls of the sleeve having an opening, and means entering laterally through the opening in the walls of the sleeve and adapted to engage a slot in a piston placed within the sleeve to expand said cylinder to the diameter determined upon by the sleeve.
5. In combination, a split expandible and 55 contractile sleeve of a diameter to encircle a heated engine piston and confine it to a predetermined diameter while maintaining its external contour unchanged, and means passing through the split of the sleeve and adapted to engage a slot in a piston placed within the sleeve to expand said cylinder to the diameter determined by the sleeve.

In testimony whereof, I affix my signature.
FRED H. SHARP.
